UNITED STATES PATENT OFFICE.

OSCAR FALKENWALDE, OF BALTIMORE, MARYLAND.

ENGINE-STARTER.

1,268,705.

Specification of Letters Patent. Patented June 4, 1918.

Application filed January 13, 1916. Serial No. 71,950.

To all whom it may concern:

Be it known that I, OSCAR FALKENWALDE, a citizen of the United States, residing at Baltimore, in the State of Maryland, have 5 invented certain new and useful Improvements in Engine-Starters; and I do hereby declare the following to be a full, clear, and exact description of the invention, such as will enable others skilled in the art to which 10 it appertains to make and use the same.

This invention relates to starters for internal combustion engines and more particularly to a manually operable starter especially designed for use in connection 15 with the engines of motor vehicles.

The invention has for its primary object to provide a simple and reliably efficient 20 starter including a flexible operating element extended rearwardly of the vehicle engine to a point conveniently near the driver thereof and including also a novel type of ball clutch in which the loose movement between the parts of the clutch is minimized.

Another object is the provision of means 25 for insuring proper lubrication of the moving parts of the starter.

Another object is the provision of means carried by the clutch for automatically 30 disengaging or releasing the parts thereof should the engine back-fire.

With these and other objects in view, the invention consists in the novel construction, combination and arrangement of parts as 35 will be hereinafter specifically described, claimed and illustrated in the accompanying drawings, in which:

Figure 1 represents a fragmental front 40 elevation of a motor vehicle illustrating the improved starter applied to use,

Fig. 2 represents a fragmental plan view of the crank shaft of the engine and the starter,

Fig. 3 represents a vertical sectional view 45 on the line 3-3 of Fig. 1,

Fig. 4 represents a transverse sectional view on the line 4-4 of Fig. 3,

Fig. 5 represents a fragmental perspective 50 view of one part of the clutch, the ball releasing fingers being shown in releasing position, and

Fig. 6 represents a fragmental perspective view of the ratchet part of the clutch.

Referring to the drawings in detail, wherein similar reference numerals designate corresponding parts throughout the several views, the numeral 5 indicates generally the body or chassis of a motor vehicle upon which is supported the dash board 6 and engine 7, having the usual crank shaft 8 55 protruding from the forward end of the crank case 9. The usual cooling fan 10 is rotatably supported in front of the cylinders of the engine 7 upon a shaft 11 and is adapted to be driven from the crank shaft 8 60 by a flexible belt 12.

The clutch, designated generally by the numeral 13, of the improved starter is mounted upon the forward end of the crank shaft 8 and includes an annular retaining 65 sleeve 14, rigidly secured to the crank shaft 8 by a locking pin 15. An annular clutch member 16 is positioned over the sleeve 14 and is secured against rotary movement with 70 relation to the shaft 8 by the locking pin 15, 75 which extends therethrough. The outer surface of the clutch member 16 is formed with spaced flanges 17, providing a groove adapted to receive the fan belt 12, whereby 80 the fan 10 is operated during rotation of the crank shaft 8. The front face of the clutch member 16 is formed with an annular groove or channel 18 in which is mounted a plurality of spaced clutch balls 19.

The other clutch member 20 is of annular 85 formation and is rotatably mounted upon the sleeve 14 forwardly of the clutch member 16 and is confined between the latter and an external flange 21 formed adjacent the forward end of the sleeve 14. The rear portion 90 of the clutch member or ring 20 disposed within the channel 18 is formed with a plurality of ratchet teeth 22 having inclined and radial faces 23 and 24, respectively, with which the clutch balls 19 are 95 designed to co-operate. A flange 25 is rigidly secured to the clutch ring 20 and also to the enlarged apertured inner end 26 of an operating arm 27, which, when operated, effects 100 a rotary movement of the clutch ring 20, causing the clutch balls 19 to become firmly wedged between the inclined faces 23 of the

ratchet teeth 22 and the clutch member 16 so as to lock the parts of the clutch against relative rotary movement in one direction. The operating arm 27 is returned to initial position, subsequent to an operation thereof, by the tension of a coil spring 28, fastened at one end to the arm 27 and at its opposite end to a part of the vehicle chassis 5.

An operating cable, chain, or other flexible element 29 is connected at one end with the curved outer extremity of the arm 27, extends across the front of the engine, under a guide pulley 30 to a point conveniently near the driver of the vehicle.

The swinging movement of the operating arm 27 under the influence of the spring 28 is limited by a relatively short arm 34 carried by an annular ball releasing member 35, fitted between the flange 25 and the forward end of the clutch member 16 and adapted to engage a relatively stationary part of the vehicle chassis, as illustrated in Fig. 1. The releasing member 35 may be rotated with relation to either of the clutch members 16 and 20 and is provided with a plurality of laterally and rearwardly directed spaced fingers 37, corresponding in number to the number of ratchet teeth 22 and being spaced a sufficient distance apart to permit free movement of the balls 19 between the fingers. During the working or operating stroke of the arm 27 the releasing member 35 is automatically moved to such position as to permit the clutch balls 19 to roll upon the inclined surfaces 23 of the ratchet teeth 22 and thus be firmly engaged with the outer wall of the channel 18 in the rear clutch member 16, as illustrated in Fig. 4, by the tension of a substantially V-shaped spring 39, having angular ends engaged in recesses 40 and 41 formed in the relatively long and short arms 27 and 34, respectively. During the return movement of the operating arm 27 under the influence of the spring 28 the relatively short arm 34 engages a part of the vehicle chassis 5 and is stopped while the tension of the spring 28 overcomes and compresses the V-shaped spring 39, thus moving the fingers 37 to the position illustrated in Fig. 5, and returning the balls 19 against the radial faces 24 of the ratchet teeth, thereby permitting a free movement of the crank shaft 8 and clutch member 16 with relation to the clutch ring 20 and operating arm 27. Should the engine 7 back fire while the driver of the vehicle is pulling the operating lever 29 rearwardly, the handle 32 is jerked out of the driver's hand and the operating arm 27 is carried back with the movement of the crank shaft 8 until the relatively short arm 34 engages the vehicle body 5, whereupon the releasing fingers 37 are moved into the position illustrated in Fig. 5, thereby mov-

ing the clutch balls 19 out of engagement 65 with the outer surface of the channel 18 and the rear clutch member 16 and permitting free rotational movement of the crank shaft 8.

The enlarged inner end 26 of the operating arm 27 is formed with an integral inwardly directed and substantially semicircular flange 43, the rear of which is normally closed by an oil ring 43^a loosely mounted between the rear clutch member 16 and the releasing member 35. An absorbent valve 44 is fitted between the flange 25 and the releasing member 35. When oil or other suitable lubricant is poured between the working parts of the clutch it falls into the flange 80 or cup 43 and is contained therein until the operating arm 27 is actuated. When the arm 27 is swung to the position opposite to that illustrated in Fig. 1, the cup 43 is inverted and the contents thereof are poured 85 into the working parts of the clutch, and thus insuring proper lubrication of the latter.

What is claimed is:

1. An engine starter including a sleeve 90 adapted to engage the crank shaft of an internal combustion engine, relatively stationary and rotatable clutch members arranged upon said sleeve, a starter arm carried by the relatively rotatable clutch member, a plurality of clutch balls arranged between said clutch members, means for moving said clutch balls to inoperative position to release said clutch members and permit independent rotational movement thereof 100 and means carried by the last-mentioned means adapted to engage a stop to release the clutch balls.

2. An engine starter including a sleeve adapted to be secured to the crank shaft of 105 an internal combustion engine, relatively stationary and rotatable clutch members mounted upon said sleeve, a starter arm carried by the relatively rotatable clutch member, a plurality of clutch balls arranged 110 between said clutch members, means rotatable with relation to said clutch members to move said balls to inoperative position to release said clutch members, means to return the starter arm to initial position subsequent to an operation thereof, and object-engaging means carried by the releasing means operable during the return movement 115 of the starter arm to move the clutch balls to inoperative position.

3. An engine starter including a sleeve adapted to be secured to the crank shaft of an internal combustion engine, relatively stationary and rotatable clutch members mounted upon said sleeve, a starter arm connected with the relatively rotatable clutch member, clutch balls arranged between said clutch members, means for moving said

clutch balls to inoperative position to permit independent rotational movement of said clutch members, and means connected with the starter arm and normally retaining the last-mentioned means in inoperative position.

4. An engine starter including a sleeve adapted to be secured to the crank shaft of an internal combustion engine, relatively stationary and rotatable clutch members arranged upon said sleeve, clutch balls interposed between said clutch members, an annular ball releasing member rotatably mounted between said clutch members and including a plurality of laterally directed fingers adapted to engage and move said balls to inoperative position to permit independent movement of said clutch members, and means connecting said releasing member and said rotatable clutch member normally retaining the releasing member in inoperative position and limiting the relative movement of the rotatable clutch member and releasing member.

5. An engine starter including a sleeve, a pair of relatively stationary and rotatable clutch members arranged upon said sleeve, clutch balls interposed between said clutch members, and an invertible lubricant containing cup carried by and movable with the rotatable clutch member.

6. An engine starter including a sleeve adapted to be secured to the crank shaft of an internal combustion engine, relatively stationary and rotatable clutch members arranged upon said sleeve, clutch balls interposed between said clutch members, a washer loosely mounted between said clutch members, an invertible lubricant containing cup carried by the rotatable clutch member and engaging said absorbent washer, and an absorbent valve interposed between said clutch members.

7. An engine starter including a sleeve adapted to be secured to the crank shaft of an internal combustion engine, relatively stationary and rotatable clutch members arranged upon said sleeve, clutch balls interposed between said clutch members, an invertible lubricant containing cup carried by and movable with the rotatable member, and a washer interposed between said clutch members and depending into and closing the rear of said cup.

8. An engine starter including a sleeve adapted to be secured to the crank shaft of an internal combustion engine, relatively stationary and rotatable clutch members arranged upon said sleeve, clutch balls interposed between said clutch members, an operating arm carried by the rotatable clutch member, means for moving said clutch balls to inoperative position to permit independent movement of said clutch members, and

means connecting the last mentioned means with said operating arm for normally retaining said ball moving means in inoperative position.

9. An engine starter including a sleeve adapted to be secured to the crank shaft of an internal combustion engine, relatively stationary and rotatable clutch members arranged upon said sleeve, clutch balls interposed between said clutch members, an operating arm carried by said rotatable clutch member, releasing means for moving said balls to inoperative position to permit independent movement of said clutch members, and an arm carried by said releasing means adapted to engage a part of a motor vehicle to automatically move said balls to inoperative position.

10. In combination, a motor vehicle including a chassis and an engine supported therein, an engine starter including a sleeve non-rotatably secured to the forward end of the crank shaft of the engine, relatively stationary and rotatable clutch members mounted upon said sleeve, clutch balls interposed between said clutch members, an operating arm carried by the rotatable clutch member, means for actuating said operating arm, means for returning said operating arm to initial position, releasing means for moving said balls to inoperative position to permit independent movement of said clutch members, an arm carried by said releasing means adapted to engage a part of the chassis of said vehicle to automatically move said balls to inoperative position, and means connecting the first and second mentioned arms to normally retain said releasing means in inoperative position.

11. In a starting device for internal combustion engines, a clutch member adapted for constant rotation with a crank shaft of an engine, concentric sleeves extending into said clutch member, an interlocking member housed within said sleeves and adapted to be shifted into engagement with said clutch member by a movement of one sleeve relative to the other, levers carried by the outer ends of said sleeves, and means connecting said levers whereby one of said levers can be moved in advance of the other.

12. In a device of the character described, in combination with an engine shaft, an annular member sleeved upon the shaft, having a ratchet-faced end adapted to be engaged by an operating crank, a pulley sleeved upon the annular member having a projecting flange, a transverse pin projecting through the shaft, the annular member and into the pulley that they may operate together, an annular collar provided with an arm and formed with a plurality of slots to severally receive a rolling element adapted to be forced into impinging relation with

the flange of the pulley, an annular hub sleeved within the collar, having cam-ways formed by recessing the hub wall and with an operating arm for rotating the hub, 5 a plurality of rolling elements severally lodged in the slots of the annular collar, means for manually operating the arm of the hub, resilient means connecting the operating arm of the hub with the arm of the

annular collar, and a spring adapted to return the hub to its initial position. 10

In testimony whereof I affix my signature in presence of two witnesses.

OSCAR FALKENWALDE.
